(57) **CLAIM**

The ornamental design for a fingerprint sensor pod design, as shown and described.

DESCRIPTION

FIG. 1 is a front perspective view showing my new design with broken lines being for illustrative purposes and forming no part of the claimed design;

FIG. 2 is a front elevational view with broken lines being for illustrative purposes and forming no part of the claimed design;

FIG. 3 is a rear elevational view;

FIG. 4 is a left side elevational view with broken lines being for illustrative purposes and forming no part of the claimed design;

FIG. 5 is a right side elevational view with broken lines being for illustrative purposes and forming no part of the claimed design;

FIG. 6 is a top plan view; and,

FIG. 7 is a bottom plan view with broken lines being for illustrative purposes and forming no part of the claimed design.
